ROBERT SUCZEK, OF PHILADELPHIA, PENNSYLVANIA, ASSIGNOR TO C. H. WHEELER
MANUFACTURING COMPANY, OF PHILADELPHIA, PENNSYLVANIA, A CORPORATION
OF PENNSYLVANIA.

CONDENSATE AND AIR REMOVING APPARATUS.

1,266,726.

Specification of Letters Patent.

Patented May 21, 1918.

Application filed May 7, 1917. Serial No. 167,061.

To all whom it may concern:

- Be it known that I, ROBERT SUCZEK, a subject of the Emperor of Austria-Hungary, residing in the city of Philadelphia, county 5 of Philadelphia, and State of Pennsylvania, have invented certain new and useful Improvements in Condensate and Air Removing Apparatus, of which the following is a specification.
10. My invention relates to apparatus for removing condensate and air or other uncondensable gas or vapor from either a surface or a jet condenser, or from kindred apparatus.
15. My invention resides in apparatus of the character referred to in which a part of the condensate, preferably the greater part, is removed by suitable pumping means, preferably a centrifugal pump, and the remainder of the condensate is removed by pumping means, preferably of centrifugal type comprising an impeller structure serving the double purpose of removing condensate and of removing air or vapor from the condenser, said impeller structure having vanes and passages for operating upon the condensate and additional vanes and passages for removing or assisting in removing the air or vapor from the condenser.
20. A further feature of my invention resides in the employment of ejector apparatus for removing air or uncondensable gases and vapors from a condenser, the combining tube or diffuser of the ejector apparatus having a jacket through which is passed cooling or injection water which after passage through the jacket is delivered back into the condenser for cooling the air or vapors to be removed by the ejector.
25. For an illustration of one of the various forms my invention may take, reference is to be had to the accompanying drawing, which is a vertical sectional view, some parts in elevation, through a condenser and associated parts embodying my invention.
30. Referring to the drawing, *J* is the body of a jet condenser which receives through the opening *K* the steam or other vapor to be condensed. Surrounding the body *J* is the water distribution chamber *C* receiving the cooling or injection water through the water supply connection *W*. In the wall of the body *J* is formed a series of nozzles *N* through which the cooling water is injected into contact with the steam entering at *K*.
The steam coming into contact with the cooling water is condensed into water, and the injection water and condensate fall through the cone, guide passage or diffuser *D* into the bottom of the body *J*, where it rises to a level, as *b*, maintained above the uppermost level of the suction of the impellers *I* and *I*₁ of the submerged centrifugal pumps *P* and *P*₁. These impellers are secured upon and driven by the shaft *S* rotating in the bearings *B*, *B* and driven by any suitable motor, as a steam turbine or electric motor, not shown. The impeller *I* discharges into the volute discharge casing *V* which delivers to any suitable point outside of the apparatus. There may be used in lieu of pump *P* a plurality of pumps *P* or pump structure comprising a plurality of impellers *I*.
The impeller *I* removes part of the entire liquid accumulating in the bottom of the body *J*, and for the sake of simplicity such liquid is called condensate, though it is a combination of injection water and condensate. Preferably the impeller *I* removes the greater part of such condensate, while the impeller *I*₁ removes a smaller part and delivers the same into the volute discharge casing *V*₁, from which it is delivered to any suitable point.
E is an ejector having one or more nozzles *n* communicating with the space *a* to which any suitable motive fluid under pressure, for example steam, is conducted through the passage *b*. Associated with the nozzle *n* is the combining tube or diffuser *d* communicating with the chamber *c* which communicates through the connection *e* with the inside of the condenser body *J* with the space below or around the diffuser *D*. Surrounding the diffuser *d* is a jacket space *f* connected by pipe *g* with the injection water chamber *C* and also by pipe *h* with the spray nozzle or rose *i* within the condenser body *J*. The diffuser *d* connects with the pipe *j* through the valve *k* with the second ejector *E*₁ which may be similar to the ejector *E* or of any other suitable type. The pipe *j* communicates also through the valve *m* with the chamber *o* communicating with a second part of the impeller structure.

5 of pump P_1 through the tubular extension p forming a part of and rotating with the impeller structure, the walls of the chamber o and the packing q forming a stuffing box for the tubular extension p . The tubular member p forms the suction opening or inlet of the impeller structure I_2 having the vanes v forming passages delivering at their outer ends into the passages between the 10 vanes v_1 of the impeller structure I_1 , whose suction opening is at u into which is delivered condensate from the condenser body J .

The operation is as follows:

First a vacuum within the condenser body

- 15 J is produced by closing the valve *m*, opening the valve *k* and setting both ejectors E and E₁ into operation, whereupon the ejector E withdraws air or uncondensable gases or vapors from within the condenser J, compresses them more or less, and delivers them in such compressed condition through the pipe *j* and valve *m* to the second ejector E₁, which further compresses them to atmospheric pressure or higher. This operation is continued until a desired degree of vacuum within the condenser J is attained. The shaft S is brought up to running speed. Thereupon water is delivered through the connection W into the chamber C and passes through the orifices or nozzles N in a plurality of streams falling through the diffuser D into the bottom of the body J submerging the pumps P and P₁, that is, the water rises to a level above the top or uppermost point of their suction orifices. Thereupon the steam to be condensed is admitted through the passage K and in coming into contact with the injection water is condensed thereby and falls with the injection water into the bottom of the body J.

Since the operation of the two ejectors E and E_1 in series would consume large quantities of steam, the desired degree of vacuum may nevertheless be attained with less expenditure of energy by opening the valve m and closing the valve k and discontinuing supply of motive fluid to the second ejector E_1 . Then there is received into the chamber σ from the ejector E both the motive fluid 45 and from the ejector E and the entrained gases or vapors withdrawn from the condenser J. These pass through the tubular extension μ into the impeller I_2 of the pump P_1 and are 50 acted upon centrifugally and raised in pressure and thrown outwardly and delivered into the spaces between the vanes v_1 of the impeller I_1 , and the condensable vapors are 55 condensed in coming into contact with the condensate passing through the impeller I_1 . The mixture of water and air is delivered 60 into the discharge casing V_1 and delivered to any suitable point, and the air separated in any well known manner.

By this construction the pump P removes 35 a part of, preferably the larger part of, the

condensate of the condenser J, and a smaller part of it is removed by the impeller I₁ which assists in condensing the vapors delivered by the impeller I₂ and assists also in raising the pressure of any air or gases removed from the condenser and delivered by the ejector E. 70

In this way only a single stage ejector need be employed with relatively smaller steam consumption, and the additional compression of the air or gases removed from the condenser J is effected by the second pump P_1 at greater economy than if the ejectors E and E_1 were both used. 75

It is further of advantage to cool the air 80 or gases removed from the condenser J, inasmuch as when cooled their volume is less, requiring correspondingly less motive fluid in the ejector E. For this purpose part of the injection water is admitted from the 85 chamber C through the pipe *g* into the water jacket *f* and delivered from the latter through the pipe *h* to the spray nozzle or rose *i* from which the water is sprayed upwardly into contact with the air or gases 90 just as they leave the condenser J and suitably cools them. By interposing the cooling jacket *f* this same cooling water assists in cooling the diffuser *d*, especially in the vicinity of its throat, to thereby reduce the 95 amount of work necessary to be performed by the motive fluid of the ejector E in effecting compression of the gases or vapors withdrawn from the condenser J. While the motive fluid and gases are undergoing compression in the diffuser *d* they tend to rise in temperature or evolve heat due to the compressing action, and the effect of water in the jacket *f* prevents such rise in temperature and so reduces the amount of work necessary to be performed by the motive fluid or, in other words, makes it possible to further reduce the amount of motive fluid. 100 105

It will be understood that for either or both of the ejectors E and E_1 may be employed any other suitable type of ejector; or in lieu of them or either of them may be used other means for removing uncondensable gas or vapor from the condensers. 110

Structure of the character embodied in the 115
pump P, herein, and such structure in com-
bination with further structure as the ejec-
tor apparatus, and such combination in co-
operation with a condenser, are not herein
claimed, but are claimed in my co-pending 120
application Serial Number 139,985, filed De-
cember 30, 1916.

What I claim is:

1. The combination with a jet condenser, of a plurality of pumps each directly removing water therefrom, one of said pumps being a wet air pump for removing air and water from said condenser. 125
  2. The combination with a condenser, of a plurality of pumps each removing water 130

- therefrom independently of the other, one of said pumps being a centrifugal pump, impeller structure in said centrifugal pump comprising parts respectively removing air and water from said condenser.
3. The combination with a jet condenser, of a plurality of pumps each directly removing water therefrom, one of said pumps being a centrifugal pump, and means whereby 10 the water acted upon by said last named pump withdraws air from said condenser.
4. The combination with a condenser, of a plurality of pumps each directly removing water therefrom, one of said pumps being 15 a centrifugal pump, and an ejector removing air from said condenser and delivering it to said centrifugal pump.
5. The combination with a condenser, of a plurality of pumps each removing water 20 therefrom, one of said pumps being a centrifugal pump, said centrifugal pump comprising a plurality of coöperating impeller structures, one of said structures removing water from said condenser, and a second of 25 said structures removing air from said condenser.
6. The combination with a condenser, of a plurality of pumps each removing water therefrom, one of said pumps being a centrifugal pump, an ejector for removing air 30 from said condenser, said centrifugal pump comprising a plurality of coöperating impeller structures, one of said structures removing water from said condenser, and an 35 other of said structures receiving air from said ejector.
7. The combination with a condenser, of a plurality of centrifugal pumps each directly removing water therefrom, a common 40 shaft driving the impeller structures of said pumps, the impeller structure of one of said pumps removing air and water from said condenser.
8. The combination with a condenser, of 45 an ejector for removing air therefrom, a cooling jacket surrounding the diffuser of said ejector, means for delivering cooling water into said jacket, and a connection from said jacket delivering the cooling water into said condenser.
9. The combination with a condenser, of 55 an ejector for removing air therefrom, a cooling jacket for the diffuser of said ejector, means for delivering cooling water into said jacket, a spraying device within said condenser near the outlet for the air delivered to said ejector, and a connection delivering water from said jacket to said spraying device.
10. The combination with a jet condenser comprising a distributor for injection water and means forming a guide passage below the same, of an ejector for removing air 60 from said condenser, a cooling jacket for said ejector, means for delivering cooling water from said distributor into said jacket, and a connection from said jacket delivering the cooling water into said condenser below said guide passage forming means.
11. The combination with a jet condenser 70 comprising a distributor for injection water and means forming a guide passage below the same, of an ejector for removing air from said condenser having an air connection therewith below said guide passage forming 75 means, a cooling jacket for said ejector, means for delivering cooling water from said distributor into said jacket, a spraying device within said condenser near the air connection to said ejector, and a connection 80 delivering water from said jacket to said spraying device.
12. The combination with a condenser, of a plurality of pumps each removing water 85 from the vacuum space thereof, one of said pumps comprising a submerged water removing impeller and an air removing impeller having an independent suction having a connection with the vacuum space of said condenser, said second named impeller delivering air into said first named impeller.
13. The combination with a condenser, of a plurality of submerged centrifugal pumps each directly removing water from said condenser, one of said pumps having water and 95 air removing impellers having independent 90 suctions, and an air connection from said condenser to the suction of said air removing impeller.
14. The combination with a condenser, of 10 a plurality of submerged centrifugal pumps each removing water from said condenser, one of said pumps having water and air removing impellers having independent 10 suctions, and an air connection from said condenser to the suction of said air removing 11 impeller, said air removing impeller delivering air from said condenser into said water removing impeller.
15. The combination with a condenser, of 11 a plurality of submerged centrifugal pumps each removing water from said condenser, one of said pumps having water and air removing impellers having independent 115 suctions, and an air connection from said condenser to the suction of said air removing impeller, said air removing impeller delivering air into said water removing impeller.
16. The combination with a condenser, of 12 a plurality of submerged centrifugal pumps each directly removing water from said condenser, one of said pumps having water and air removing impellers having independent 12 suctions, and means for removing air from said condenser and delivering it at higher pressure into the suction of said air removing impeller.
17. The combination with a jet condenser, of a plurality of submerged centrifugal pumps each removing water from said con- 13.

4
denser, one of said pumps disposed within the body of said condenser, another of said pumps comprising a water removing impeller whose suction is in communication with the water space of said condenser, an

5 air removing impeller having an independent suction, and an air connection from said

condenser above the water therein to the suction of said air removing impeller.

In testimony whereof I have hereunto affixed my signature this 3rd day of May, 1917.

ROBERT SUCZEK.
